RECEIVER SUPPORT

Edgar H. Hand, Jarrettown, Pa.

Application April 12, 1935, Serial No. 16,005

2 Claims. (Cl. 179—156)

My invention relates to receiver supports, and is particularly adapted for use with hearing-aid receivers, and receivers which are supported in position on the head of the user so that the hands 5 may be left free for the performance of various tasks.

Devices of the general character described have been heretofore made, but there have been several difficulties which have made their use 10 unsatisfactory. In using the previous known conventional type of headband support for the receiver, it has been found that if a sufficient amount of tension is placed upon the headband to properly position and hold the receiver, 15 the pressure upon the head of the user becomes very oppressive, and after a long period of time, quite painful; on the other hand, if the tension of the headband is relieved, the receiver is so loosely held that foreign sounds will interfere 20 with the correct reception of sound being transmitted through the receiver.

Another difficulty that has been found is that while a device may operate fairly satisfactorily with one type of head, it will be utterly unsatisfactory for another type, and, consequently, there 25 will result faulty reception or extreme discomfort to the user.

An object of my invention is to eliminate the 30 difficulties just described and to provide a receiver support which is simple in construction, economical to manufacture, and which, while achieving the objects just described, is not rendered unsightly or inconvenient for use.

Another object is the provision of a device in 35 which the pressure desired for perfect reception may be relieved to a large extent during periods when close attention is not necessary, and yet permit the device to remain in position for instant use and adjustment for close attention 40 when needed.

Another object is the provision of a device in 45 which the receiver is supported so that a large measure of universality of movement of the receiver to various positions is made possible as to place the receiver in the exact proper position for good reception, regardless of the shape of the head or ear of the user.

Other objects will appear hereinafter.

My invention, therefore, comprises a headband, a receiver support carried by said headband, a positioning and clamping member for placing and maintaining the receiver in proper position for good reception, and adjusting means for readily increasing or decreasing the tension 55 of the positioning and clamping member.

My invention may be best understood by reference to the accompanying drawing, in which:

Figure 1 is a perspective view of my device and a bone conduction receiver in unassembled 60 relation.

Figure 2 is a partial front elevation of my device with the bone conduction receiver assembled in proper relation,

Figure 3 is a side elevational view of my device assembled with a bone conduction receiver, and shows the relation of the parts in an exaggerated manner when the adjusting means has been moved to relieve the tension of the positioning and clamping member,

Figure 4 is a side elevational view of my device assembled with a bone conduction receiver having its magnet at the bottom of the receiver,

Figure 5 is a side elevational view of the device shown in Figure 3 and illustrates the adjusting member at a different position, and

Figure 6 is a partial side elevational view of a modified form of my device, which may be used with the ordinary telephone-type receiver or headphone; in dotted lines is shown the relation of the parts when the tension on the clamping member is removed by the adjusting member.

My preferred form of construction comprises a headband 10 formed, preferably, of a relatively inflexible strip of metal formed into an arcuate or crescent shape. One end of the band 10 is preferably outwardly and upwardly curled, as at 11, so as to provide a more comfortable contacting surface for the head.

At the opposite end of the device is provided an annular opening through which is passed a pin 12, the opposite ends of which are enlarged, for a purpose later to be described. A yoke 13 is, preferably, provided with an upwardly extending arm portion 14 in which is formed an annular opening for the reception of pin 12. Preferably, the annular opening in arm 14 is relatively larger in diameter than is the shank of pin 12, and, consequently, a considerable amount of play is allowed at this point for permitting the arm 14 to be twisted on the shank, as well as being swung on said shank. Likewise, the pin 12 is of sufficient length to permit of a relatively large amount of movement of said arm 14 longitudinally of pin 12. After the arm 14 and band 10 are assembled, the small end of pin 12 may be riveted so as to secure properly the parts in their desired relation. The yoke 13 is, preferably, formed of spring metal and the fork members 15 are preferably somewhat attenuated so as to provide a measure of flexibility. The lower extremities of the members 15 are bent inwardly toward each other, and are adapted to lie in the same plane; they thus form a pair of cooperating tong-like ends.

The bone conduction receiver 16 has the customary casing 17 which is formed of a non-conducting material, and carries the customary rectangular-shaped cap 18 which is adapted to rest in close proximity to the mastoid bone. On the opposite vertical sides of cap 18 are provided a pair of oppositely opening recesses 19 which are 55

of such dimension as to receive loosely the cooperating tong-like ends of yoke 13. Since the yoke 13 is formed of spring metal, its lower ends may be spread until a sufficient amount of space is provided for the straddling of cap 18, and when the parts are in proper position, the release of the ends of yoke 13 will cause them to seat in the recesses 19. Because of the loose fit of the ends in recesses 19, a considerable amount of movement 10 of the receiver in many directions is possible, even though supported by the yoke 13.

On the lower face of headband 10 is preferably suspended a positioning and clamping member 20. The member 20 comprises an elongated flat spring strip 21 of arcuate shape, and adjacent one end thereof I provide an annular opening through which may be received a rivet 22 which passes through a like opening in band 10 and secures the parts together. The arc of member 20 is 20 taken on a substantially smaller radius than that of the band 10, and, consequently, the tendency of the member 20 is to press inwardly from the band 10. The end of the member 20 opposite the end which is secured to the band 10 is preferably formed into a U-shaped seat 23 which is of sufficient size to receive the casing 17 of receiver 16.

The lower end of the positioning member 20, that is, the end carrying the seat 23, may be passed through the upper portion of yoke 13 and the receiver 16 may then be engaged by the tong-like ends of yoke 13. While the seat 23 is finally arranged on the opposite side of yoke 13 from that upon which the spring strip 21 of member 35 20 is positioned, there is, preferably, no contact between the yoke and the positioning member 20 at any place. This permits relatively free movement between the parts, and allows the receiver to rest in the correct position without interference 40 between the parts.

A slidable sleeve 24 has an appropriate slot therein which is of sufficient dimensions to receive slidably headband 10 and clamping and positioning member 20. In Figure 1, the sleeve 45 24 is at its uppermost extremity and in this position the clamping member may exert its greatest force inwardly to press the receiver 16 against the head of the user. However, such a great amount of force may not be necessary, or desirable, and, consequently, the sleeve may be slid 50 downwardly to the position indicated in Figure 3, and thus the clamping member 20 and its seat 23 are held outwardly so that a smaller amount of force is exerted on receiver 16 to press the same against the head of the user.

As before stated, the parts in Figure 3 are illustrated in a somewhat exaggerated position since the seat 23 is entirely out of contact with the receiver 16. However, in practical operation, the 60 upper part of seat 23 will be pressing slightly against the upper part of receiver 16 even when the pressure is released by lowering sleeve 24. As can be seen from Figures 3 and 5, the upper part of seat 23 is adapted to press more tightly 65 against the upper part of the receiver 16 because of the fact that in this particular type of receiver, the magnet is located at the top of the receiver, and that is the position which it is desired to have in close contact with the head.

In the form shown in Figure 4, the magnet is 70 located adjacent the bottom of receiver 25 and the seat 26 of positioning and clamping member 27 is differently formed from seat 23, although the spring strip 28 is substantially the same as 75 spring strip 21 in other respects. Likewise, the

headband 29 is similar to headband 10. A rivet 30 is similar to rivet 22, and holds positioning and clamping member 27 and headband 29 together. Sleeve 31 is similar to sleeve 24, and operates in a similar manner. Pin 32 is like pin 5 12, and the same is true of yoke 33 which finds its counterpart in yoke 13. Due to the change of angle of seat 26 from that of seat 23, the greatest amount of pressure that can be exerted by the seat is at its lowermost point where it presses the 10 magnet of receiver 25 firmly into position.

The modified form of my structure, which is shown in Figure 6, comprises a headband 34 which in all important particulars is like the headband 10 of my preferred form of construction. However, a bracket 35 is pivotally secured to one end of headband 34, and this bracket serves a purpose analogous to yoke 13 in the case 15 of my preferred form of construction. A vertically arranged pin 36 is adapted to carry receiver support 37 which in turn supports a telephone or headphone type of receiver 38. My positioning and clamping member 39 is formed generally of an elongated strip metal, and has one end thereof secured to the outer face of 20 band 34 by an appropriate rivet 40. A sleeve 41 slidably receives the main body of my clamping member 39, and headband 34, and serves to bring them together as the sleeve 41 is slid downwardly. The lower end of member 39 is provided 25 with a contacting portion 42 which is adapted to press upon the outer face of receiver 38 when sleeve 41 is brought downwardly to increase the tension upon clamping member 39. When the sleeve is moved upwardly the tension of the 30 clamping member 39 raises it to the position indicated in dotted lines, and frees the ear of the user from the greater pressure afforded when 35 close attention is required.

It can be seen from the foregoing that an important underlying object of the various forms I have described is to press the receiver into the best position possible for the user so that he may 40 hear with the greatest distinctness. Likewise, another underlying similarity is that this pressure may be easily and quickly removed by simple movement of a sliding sleeve.

While I have shown and described my preferred forms of construction, I do not wish to be limited to the details herein shown and described, but wish to avail myself of all variations 50 coming within the scope of the appended claims.

I claim:

1. A device of the character described comprising a headband, a receiver supporting yoke 55 pivotally and loosely secured to one end of said headband, and a positioning and clamping member secured to the lower face of said headband and having its lower end forming a receiver seat and passed through said yoke so as to press a 60 receiver supported by said yoke into close contact with the head of the user.

2. A device of the character described comprising a headband, a receiver supporting yoke 65 pivotally and loosely secured to one end of said headband, a positioning and clamping member secured to the lower face of said headband and having its lower end forming a receiver seat and passed through said yoke so as to press a receiver supported by said yoke into close contact 70 with the head of the user, and means for varying the inward pressure of said positioning and clamping member.
